United States Patent Office.

WILLIAM JOHNSTON, OF APPLETON, WISCONSIN.

Letters Patent No. 79,474, dated June 30, 1868.

IMPROVED CLOTHES-DRIER.

The Schedule referred to in these Letters Patent and making part of the same.

TO WHOM IT MAY CONCERN:

Be it known that I, WILLIAM JOHNSTON, of Appleton, in the county of Outagamie, and State of Wisconsin; have invented certain new and useful Improvements in "Clothes-Driers;" and I do declare that the following is a true and accurate description thereof, reference being had to the accompanying drawings, and to the letters of reference marked thereon, and being a part of this specification.

The nature of my invention consists in constructing a neat, cheap, and durable "clothes-drier," in such a manner that it can be folded up against the wall when not in use, and upon which it is secured. To accomplish this purpose, I construct a pendent bracket, composed of ornamental metallic sides A A, connected together by the frame-rods B C, the frame-rod B being provided with the proper facilities for securing the apparatus to the side wall of the room. E E E E are bars upon which the garments to be dried are hung. F is a fulcrum-rod, secured to the sides of the apparatus by a screw, G, at each end, with sufficient space between the same to receive the lower ends of the movable arms H of the rods E, which are secured to and oscillate freely upon the screws which secure the ends of the fulcrum-rod F to the sides of the apparatus, the other ends of said arms being secured to the clothes-bars by passing into a longitudinal slot, I, in the clothes-bars E, and there retained by rivets J. The movable arms H, being of different lengths, when dropped forward to a horizontal position, and resting upon the frame-rod C, suitable spaces are left between the bars E for the reception of clothes to be dried.

What I claim as my invention, and desire to secure by Letters Patent, is—

1. The movable metallic arms H, folding into each other and oscillating upon a common fulcrum, operating in the manner described and for the purposes set forth.

2. The combination and arrangement of the bracket-sides A A and the frame-rods B C with the fulcrum-rod F, the metallic movable arms H, and the bars E E E E, with the slot I and rivet J, when operating in the manner specified and for the purposes set forth.
